CLAIM

The ornamental design for jewelry, as shown and described.

DESCRIPTION

The patent or application file contains at least one drawing/photograph executed in color. Copies of this patent or patent application publication with color drawing(s)/photograph(s) will be provided by the Office upon request and payment of the necessary fee.

FIG. 1 is a front view of jewelry showing my new design;

FIG. 2 is a rear view thereof;

FIG. 3 is a side view thereof;

FIG. 4 is an opposite side view thereof;

FIG. 5 is a top perspective view thereof;

FIG. 6 is a bottom perspective view of thereof; and,

FIG. 7 is a partial enlarged front view of FIG. 1.

The dash-dot broken lines depict enlargement areas and form no part of the claimed design.

1 Claim, 5 Drawing Sheets
